UNITED STATES PATENT OFFICE.

RAOUL STEPPE, OF NIEUKERKE-WAES, BELGIUM.

BUILDING BLOCK.

Application filed February 6, 1926, Serial No. 86,503, and in Belgium February 4, 1925.

This invention relates to the building industry and has more especially for its object, a new and improved constructive form of agglomerated blocks which, when juxtaposed, will constitute a compact whole, reinforced by continuous or noncontinuous metal-bars, both vertically and horizontally.

This invention chiefly contemplates to obtain a theoretically perfect arrangement 10 of the reinforcement-bars, in so far as the vertical reinforcement assists in withstanding lateral thrust or stresses in any direction.

This result is obtained by providing the 15 blocks with vertical perforations arranged alternately on both sides of the vertical plane passing through the longitudinal axis of the blocks. Owing to this arrangement, the reinforcement bars or rods shall be 20 alternately located on both sides of the median vertical plane of the wall.

The invention also provides the means for facilitating the location of the vertical reinforcement bars or rods, by giving the 25 perforations receiving same, a much larger section than the cross-section of said rods. The empty space around the reinforcement is then filled with concrete or any suitable binding-material. Besides, such perforations 30 have the advantage of producing after the introduction of binding material, assembling projections between the successive layers of blocks.

Last, this invention contemplates suitable 35 constructive forms of consolidation blocks and of corner-blocks for strengthening-pillars, partition walls, corner walls and the like.

The accompanying drawings illustrate by 40 way of example, some execution forms of this invention. In said drawings:

Fig. 1 is a plan view of a block-unit.

Fig. 2 is a front view of Fig. 1.

Fig. 3 shows a half-block.

Figs. 4 and 5 illustrate blocks for strengthening-pillars, for partition-walls and for walls-heads.

Figs. 6 and 7 show two successive layers of blocks for wall with strengthening pillar.

Figs. 8 and 9 are two successive layers of blocks for corner walls.

Similar reference figures relate to similar parts in the drawings.

Referring to the drawing: the block-unit 55 (or brick) 1¹ has the same width as the

wall to be erected; said block shows on its upper surface, and along its center line, a rectangular groove 2, intended to be filled with binding material and to receive, if desired, a metal rod 3; by juxtaposing 60 blocks 1¹ and half-blocks (or half-bricks) 1², each layer will show a continuous groove or channel 2 into which can be laid a continuous reinforcement rod or bar 3. Every block unit 1¹ presents two rectangular vertical perforations or holes 5, passing completely through same; said holes are arranged one on each side of the median groove or rill 2, at every last fourth of the brick-length. 70

The half-block unit 1² has only one hole 5 in the half of its length, also along its center line.

By this arrangement, the holes or perforations 5, owing to the superposition of the 75 blocks, form continuous vertical canals in which is inserted the vertical reinforcement 6 of the wall, said reinforcement consisting of metal rods or bars of suitable length.

It will be seen that the section of the vertical holes is larger than the cross-section of the metal rods 6; this is intended to facilitate the insertion of long rods 6 in said holes. 80

The binding material 4, entering the holes 5, constitutes, even when the vertical reinforcement is dispensed with, an anchorage for the superposed bricks, by the production, in each hole, of a projecting nose of binding material which adheres with the next underlaying brick. The binding material 4 laid in the horizontal groove of the blocks has the same effect as regards the superposed layers of blocks. 90

With reference to Fig. 4, the block 1⁴, therein illustrated, is much wider than the 95 plane block-unit and ends in a tail corresponding to one half of a block-unit; said tail is perforated with a vertical hole located at the same place as in the half block-unit 1². In its wider part, the block 1⁴ is bored with 100 two vertical holes intended to receive the metal-reinforcement.

Said block 1⁴ is used together with the strengthening half-blocks 1³, which are somewhat less wide than the half width of 105 block 1⁴, and have the same length as the latter.

Figs. 6 and 7 illustrate the manner of using said blocks 1⁴ and 1³ for two successive layers. The block-units 1¹ are superposed 110

on blocks 1³ and the tails of blocks 1⁴ are used as half-blocks for obtaining the usual alternating vertical joint. By their superposition, the blocks 1³ and 1⁴ constitute a 5 reinforced strengthening of the wall.

With reference to Figs. 8 and 9, the blocks 1³ and 1⁴ are illustrated as parts of a corner wall. The blocks 1⁴ are juxtaposed alternately with one block 1³ towards one of the 10 panes of the wall and with one towards the other pane.

Other combinations and applications of the block-units 1¹ half-blocks 1² and strengthening blocks 1³ and 1⁴ are possible, 15 but fall of course within the scope of the present invention. Similarly it shall be noted that the alternative bilateral arrangement of the reinforcement vertical rods will have as result the formation of a zone of 20 higher resistance on both sides of the median-plane of the wall. This is of great advantage when the blocks are used for the erection of walls subject to a horizontal or oblique thrust directed against one or the 25 other side of the wall.

From the foregoing it will be seen that blocks such as described can be used, by modifying their size or section (for instance by giving same a curved section) for erecting 30 building-walls, tanks, pillars, chimneys, and the like, which will then form a compact whole, reinforced as required both in vertical and horizontal direction.

The manufacture of such blocks present 35 no special technical difficulty; same can be manufactured with the usual brick-presses provided with suitable means for obtaining the perforations 5 and groove 2.

I claim:

1. A building structure of the character 40 described, comprising a plurality of blocks each including a body provided along one longitudinal contacting edge with a groove and with vertical openings arranged in staggered relation on opposite sides of the 45 groove, longitudinal and vertical reinforcing wires receivable in the grooves and openings of adjacent blocks, cementitious binding material for anchoring the rods in the blocks and the blocks together, substantially 50 as and for the purposes set forth.

2. A building block as claimed in claim 1, wherein the longitudinal groove is arranged medially between the inner and outer faces of the body of each block, substantially as 55 and for the purposes set forth.

3. In a building structure, a plurality of blocks each of which are longitudinally grooved on one engaging edge and are provided on opposite sides of said grooves with 60 vertical openings positioned in staggered relation, reinforcing rods anchored in said grooves and openings, the ends of certain of said blocks being reduced to its vertical longitudinal median plane and said reduced 65 portion being enlarged in oblong form in cross-section, the ends of certain other blocks being enlarged in T-shape formation in cross-section for contacting engagement with the first mentioned enlarged blocks the 70 enlarged portions of said blocks being also apertured, and reinforcing rods anchored therein.

In testimony wherof I have signed my name to this specification.

RAOUL STEPPE.
